UNITED STATES PATENT OFFICE.

RETLOW ROLKERR, OF OAKLAND, CALIFORNIA.

FLUID-COMPRESSOR.

1,376,291.

Specification of Letters Patent. Patented Apr. 26, 1921.

Application filed February 26, 1918. Serial No. 219,295.

To all whom it may concern:

Be it known that I, RETLOW ROLKERR, a citizen of the United States, residing at Oakland, in the county of Alameda and 5 State of California, have invented new and useful Improvements in Fluid-Compressors, of which the following is a specification.

This invention relates to a fluid compressor of the rotary type.

10 It is the principal object of this invention to provide a machine for compressing fluids and liquids, which is compact in its design, may be adapted for compressing a fluid to a desired number of atmospheres, 15 and which is composed of but two movable parts adapted to rotate within the case of the compressor and to continuously operate to gradually raise the pressure of the fluid passing therethrough.

20 Another object of this invention is to provide a rotary fluid compressor composed of few parts which may be readily interchanged and repaired, when desired, and which are assembled and driven in a manner to eliminate the major portion of wear, 25 due to the movement of its rotors.

Further objects will appear hereinafter.

The present invention contemplates the use of a fixed outer casing and a pair of 30 intermeshing runners having convolute walls, one of said runners rotating concentrically with the horizontal axis of the case and the other rotating eccentrically thereto, whereby relative movement between the 35 two walls will be effected and a fluid progressively transferred from the outer annular chamber of the casing and compressed to pass around a central eduction port.

40 The invention is illustrated by way of example in the accompanying drawings, in which—

Figure 1 is a view in transverse vertical section, disclosing the vital elements of the 45 compressor at a point in the cycle of operation of the rotor at which a fluid is being drawn into the machine.

Fig. 2 is a view similar to that disclosed in Fig. 1, showing the rotor as having advanced a half revolution and at a point of 50 exhaust in its cycle of operation.

Fig. 3 is a view in vertical section through

the machine as seen on the line 3—3 of Fig. 2.

Fig. 4 is a view of the compressor in 55 horizontal section as seen on the line 4—4 of Fig. 1.

Fig. 5 is a view in elevation illustrating the eccentrically moving runner as disassociated from the case. 60

Fig. 6 is a view in elevation illustrating the concentrically moving runner as disassociated from the compressor.

Fig. 7 is a view in perspective further illustrating the detailed construction of the 65 runner disclosed in Fig. 5.

10 indicates the casing of the compressor and is here shown as being formed of end plates 11 and 12 which are bolted to an annular wall 13, interposed therebetween. 70 The end plates are formed with outwardly extending feet which provide a base by which the compressor may be fixed as desired. Preferably the plates have an upper semicircular portion concentric with the 75 annular wall 13 for which they form opposite ends. Bearings 14 are formed upon the outer sides of the two plates and are concentrically disposed in relation to the enclosing wall 13. These bearings are 80 concentrically threaded to receive stuffing boxes 15 by which eduction pipes 16 are secured at the opposite sides of the casing.

Central, annular bores 17 are formed through the bearings and concentric therewith. The hubs 18 of disks 19 and 20 are rotatably disposed within the bearings and are further supported by antifriction bearings 21. The disks 19 and 20 are circular and concentric with their hubs which, as 90 shown in the drawings, are shown as tubular. Upon the smooth parallel adjacent faces of the disks are formed convolute grooves 22. These grooves are of the configuration shown in Fig. 6 of the drawings 95 where it will be seen that they form a continuous convolute spiral extending from a point adjacent to the rotatable axis of the disks to a point near their outer circumference. These grooves are adapted to receive 100

a convolutely wound vane 23 which corresponds in configuration to the grooves and rests with its opposite edges seated within the grooves. This vane is comparatively

thin in thickness and is fixed between the two disks 19 and 20 and within the grooves by means of disk bolts 24 distributed at intervals around the circumference of the two 5 disks.

It is to be noted that the disks 19 and 20 are adapted to rotate concentrically of the horizontal axis of the casing. The rotation of the unit comprising the disks 19 and 20 10 and the vane 23 is effected by gears 25 and 26 secured upon a drive shaft 27 and particularly shown in Fig. 4 of the drawing. This shaft is journaled within the opposite end walls of the casing and is disposed on a 15 line below the horizontal axis of the case. The gears 25 and 26 are in constant mesh with gear teeth formed around the periphery of each of the disks 19 and 20 and the floating member.

20 Mounted between the end disks 19 and 20 is an eccentrically moving runner which is supported in a floating manner in relation to the concentrically moving runner comprising the two disks and the vane 23. This 25 eccentric runner is particularly disclosed in Figs. 5 and 7 of the drawings, where it will be seen to comprise a pair of circular end walls 28 and 29 cast integral with a convolute vane 30. The wall of this 30 vane is of greater thickness than the wall of the vane 23, as shown by comparison in Fig. 3. This vane is inclosed by a cylindrical wall 31, with which it is united at its outer end. The outer diameter of the 35 wall 31 is considerably less than the outer diameters of the side flanges 28 and 29 formed integral therewith. This provides an annular air space between the two flanges and around the wall.

40 Transversely extending cooling fins 32 are formed integral with the flanges 28 and 29 and are distributed around the annular wall 31, being arranged radially in relation thereto. A series of large perforations 33 45 is formed through the walls of the flanges to accommodate the clamping bolts 24 of the disks 19 and 20 and also to allow these disks to have relative movement in relation to the flanges without limitation thereby. 50 An examination of Figs. 1 and 2 will disclose the utility of the enlarged perforations 33 and the manner in which the bolts 24 are allowed free movement within the perforations.

55 Referring more particularly to Figs. 1 and 2, it will be seen that the cylindrical wall 31 of the eccentric runner not only circumscribes the vane 30 but also incloses the vanes 23 of the concentric runner. This 60 forms a cylindrical compression chamber within which two convolute runners are disposed and are arranged in eccentric intermeshing relation to each other. As previously stated, the concentric runner A is 65 driven by gears 25 and 26 and a drive shaft

27. This same thing is true of the eccentric runner, although this runner is permitted to float within the casing, being held in its eccentric position by these gears.

In order to maintain the two runners in 70 proper relation to each other idler gears 35 and 36 are disposed upon a shaft 37, lying in the same horizontal plane with the drive shaft 27 and upon the diametrically opposite side of the casing within which it is 75 mounted. Thus it will be inferred that the two runners A and B will have uniform movement in relation to each other and their common drive shaft. The disposition of these gears also limits the floating movement of the runner B to a vertical plane, 80 while allowing it to continuously rotate in synchronism with the runner A; it being understood that the relative movement between the two runners is effected by the eccentric disposition of the vane 30 in relation to the concentrically arranged vane 23.

An induction port 38 is formed through the cylindrical wall 13 of the case and communicates with an annular chamber formed 90 by the case and the cylindrical wall of the runner B. This wall of the runner is formed with openings at equal intervals around its circumference and thus allows the air to pass into the cylindrical chamber within the 95 runner B. When the runner B receives the fluid through its cylindrical wall it immediately proceeds to advance this volume of fluid between the vanes of the two runners as they rotate and thus progressively compress the fluid as it is carried to the center 100 of the runner A and allowed to pass out through the eduction pipes 16 in communication with the tubular hubs of the runner disks 19 and 20.

105 In operation, the machine is assembled, as particularly disclosed in the drawings and its drive shaft 27 provided with suitable power for rotation. As this shaft rotates in the direction of the arrow a, as shown 110 in Figs. 1 and 2, it will cause the runners A and B to rotate in the direction of the arrow b in the same figures. Due to the fact that the runner A is provided with 115 fixed hubs, it will rotate continuously upon a single horizontal axis as driven by the drive shaft 27 and its gears. At the same time that the runner A is rotating concentrically, the drive shaft and gears will rotate the runner B eccentrically.

120 An examination of Figs. 1 and 2 will disclose the fact that the pitch of the convolute vanes is equal and that the extreme space between these vanes in their overlapping position is equal to the combined 125 thickness of the vane 23 and the vane 30. Furthermore, due to the eccentric disposition of the vane 30 in relation to the vane 23, a series of crescent shaped pockets will be formed between the vanes at all times. 130

The two vanes thus form a series of pockets of reduced capacity as they approach the axis of the runners and reach the central compartment where they are in communication with the eduction pipes.

As shown in Figs. 1 and 2, a termination pocket C is formed by the cylindrical outer wall of the runner B and a portion of the first convolution of its vane 30. The pocket thus formed is closed by the outer end of the vane 23 which continuously moves concentric with the axis of the machine. When the vane 23 is in contact with the inner surface of the wall 31 a second crescent-shaped compartment D will be formed by portions of the two vanes. This compartment will be terminated by contact of the two vanes at a point along the vertical axis of the casing. After reaching this point the two vanes will again separate to form a compartment E of reduced volume. This compartment is followed by a compartment F, after which a smaller compartment G occurs. In the present instance a compartment H, of smaller volume than any of the preceding ones, is formed and this in turn communicates with a central chamber I in direct communication with the eduction pipes 16 extending through the opposite hubs of the disks 19 and 20.

Assuming that the compartment C is filled with a fluid and that the two runners are rotating at constant speed, it will be evident that the half rotation of the two runners will transfer the fluid progressively from the position of the compartment C into that occupied by the compartment D. The relation of the two vanes, after the runners have rotated a half of a revolution, is particularly shown in Fig. 2. A comparison of this view with the preceding one will disclose the fact that due to the eccentricity of the two convolute runners the vane 30 will have moved vertically and downwardly until it has encountered the upper face of the vane 23. This movement will separate the outer end of the vane 23 from the inner surface of the cylindrical wall 31 of the runner B and allow direct communication between the compartment C and the compartment D. This change in relation between the two vanes will cause the fluid to be forced from between the portion of the compartments at the left-hand side of the vertical axis of the machine and into the adjacent compartment which is of reduced capacity.

Continuous operation of the machines will eventually transfer the fluid originally in the compartment C through the compartments D, E, F, G and H successively and into the central compartment I. In the event of each transfer the fluid will be forced into a compartment of smaller capacity and compressed. It will thus be seen

that with the device here disclosed a gradual compression will be effected which might be termed a six-stage compression. It will be manifest that continuous rotation of the two runners will cause them to rotate at the same rate of speed and will effect a relative movement of the two vanes which will continuously compress a fluid passing therebetween.

It will thus be seen that the compressor here disclosed is composed of few elements, simple in construction, which are not subjected to excessive wear, and which will operate in a continuous manner and without objectionable vibration to continuously and progressively compress a fluid.

While I have shown the preferred construction of my fluid compressor as now known to me, it will be understood that various changes in the combination, construction and arrangement of parts may be made by those skilled in the art without departing from the spirit of my invention.

Consideration of the device here shown will disclose the fact that the structure embodied in the present invention may be readily adapted for use as a pump, in which case the fluid or liquid passing therethrough will not be confined in its course of travel but will be forced along the volute channel by the action of the volute vane operating therein.

Having thus described my invention, what I claim and desire to secure by Letters Patent is—

1. In a fluid compressor, a pair of volute vanes disposed about a single shaft, a means for rotating one of said vanes concentric with the shaft and the other of said vanes eccentric thereto, whereby the two vanes will coöperate to force a volume of fluid along and between their convolutions and to the center thereof.

2. In a fluid compressor, a rotatable runner having a fixed axis, a second rotatable runner having a floating axis, and means whereby relative change of position of the two runners during their rotation will cause a fluid passing therebetween to be compressed.

3. In a fluid compressor, an outer casing, bearings in the opposite ends thereof, a runner supported to rotate by said bearings and upon a single axis, a second runner disposed within the case and adapted to rotate upon a floating axis, and means for constantly rotating both of said runners irrespective of the change of position therebetween.

4. A fluid compressor comprising a circular casing, a runner supported therein to constantly rotate upon the axis of the casing, a volute vane forming a part of said runner and disposed with its axis concentric thereto, a second runner having a floating

axis, and means whereby relative movement may be effected between the two runners to cause a fluid to be progressively forced along and between the convolutions of the vane, 5 whereby it will be compressed and will be allowed to escape at the axis thereof.

5. A fluid compressor comprising an inclosing case, a runner therein and rotatably supported thereby, a volute vane having a 10 plurality of convolutions and forming a part of said runner, the spaces at the sides of said vane being closed, a floating runner having a cylindrical wall circumscribing the volute vane, means for simultaneously 15 rotating the two runners in a single direction, and means whereby relative transverse movement may be effected between the runners to force a fluid along and between the convolutions of said volute vane 20 and thereby compress it to be emitted from an eduction port at the center of the first named runner.

6. A fluid compressor comprising a casing having an induction port through the 25 wall thereof, a concentrically rotating runner inclosed within said casing and supported by bearings at the opposite ends thereof, said runner comprising a pair of spaced circular disks, a volute vane having 30 a plurality of convolutions and secured between the disks and concentric with the axis thereof, a floating runner having a cylindrical wall inclosing the vane of the first named runner and disposed between the end disks 35 thereof, induction ports through said wall of the circumferential floating runner, a volute vane emanating from the wall of the floating runner and extending with its convolutions between the convolutions of the 40 first named runner, and means whereby rotation of the two runners at a single speed and in a single direction will effect relative movement between the two volute vanes and thereby progressively transmit volumes of a 45 fluid from the casing along and between the vanes to the center thereof, and eduction ports formed through the disks of the concentrically rotating runner for allowing the escape of the fluid compressed between the 50 runner vanes.

7. In a fluid compressor, a pair of rotatable runners, a casing inclosing said runners, means whereby one runner will be adapted to rotate concentrically with the 55 axis of the casing, means for supporting the other runner in a floating position in relation to said concentrically rotating runner, means for simultaneously driving the runners in a continuous direction and at a single speed irrespective of the change of position of the 60 floating runner to the concentric runner, and means whereby the two runners will have relative movement in relation to each other and will thereby compress a fluid passing 65 therebetween.

8. In a fluid compressor, a casing, sets of gear pinions rotatably secured within said casing and upon diametrically opposite sides thereof, a pair of intermeshing runners disposed within the casing and between the 70 pinions, gears formed around the peripheries of said runners and in mesh with said pinions, and means whereby one of said runners will be provided with a vertical floating movement while rotated continuously with the other runner and at the same speed.

9. A fluid compressor comprising a case, a concentrically rotating runner therein, said runner consisting of a pair of circular 80 disks spaced in relation to each other and journaled in the opposite ends of the case, a volute vane positioned between the disks and concentric with the axis thereof, bolts clamping the said disks together to bind 85 the vane, a floating runner circumscribing the volute vane and disposed between the disks, means whereby said runner may have movement in relation to the concentrically rotating runner without obstruction from 90 the clamping bolts thereof, and means whereby continuous rotation of the two runners at a single speed will effect a movement of the floating runner and cause air to be forced inwardly along the volute vane to 95 compressed thereby.

10. In a device of the character described, an outer case comprising a cylindrical wall, end plates bolted to the opposite sides of said wall forming an inclosed compartment, 100 and circular recesses formed by the wall and upon diametrically opposite sides of the axis thereof for receiving operating gears.

11. In a device of the character described, a runner comprising a pair of separate circular end plates, tubular hubs extending oppositely from said plates and concentric therewith, volute grooves formed in the adjacent faces of the plates, a volute vane adapted to seat within said grooves to form 110 a continuous volute compression chamber having a series of convolutions, a series of gear teeth formed around the peripheries of said plates, and driving gears adapted to produce rotation of the runner so formed. 115

12. In a device of the character described, a floating runner comprising a cylindrical wall having ports formed through it and distributed therearound, a volute vane inclosed by said wall and extending throughout a series of convolutions, parallel spaced flanges extending from the wall, and gear teeth formed around the peripheries of said flanges to afford driving means for the runner. 120

13. In a device of the character described, a floating runner comprising a cylindrical wall having ports formed through it and distributed therearound, a volute vane inclosed by said wall and extending throughout 130

out a series of convolutions, parallel spaced flanges extending from the wall, and radially extending cooling fins disposed between the flanges and spaced at intervals around the 5 wall of the runner.

14. In a device of the character described, a floating runner comprising a cylindrical wall having ports formed through it and distributed therearound, a volute vane in 10 closed by said wall and extending throughout a series of convolutions, and parallel spaced flanges extending from the wall having enlarged openings through which bolts may extend in relation to which the 15 runner is movable.

15. An air compressor comprising a circular case, a concentrically rotating runner inclosed within said case and within which a volute passageway is formed, a floatable 20 runner having a circumferential wall circumscribing the volute portion of the concentric runner, and a volute vane forming a part of the floatable runner and extending along the volute passageway of the concentric runner.

16. An air compressor comprising a circular case, a concentrically rotating runner inclosed within said case and within which a volute passageway is formed, a floatable 30 runner having a circumferential wall circumscribing the volute portion of the concentric runner, a volute vane forming a part of the floatable runner and extending along the volute passageway of the concentric runner, means for simultaneously 35 rotating both of said runners, and means whereby the volute vane of the floating runner will be caused to move radially back and forth across the volute passageway 40 of the concentric runner whereby a series of alternately occurring compression chambers will be formed within the volute passageway.

17. An air compressor comprising a circular case, a concentrically rotating runner inclosed within said case and within which a volute passageway is formed, a floatable runner having a circumferential wall circumscribing the volute portion of 50 the concentric runner, a volute vane forming a part of the floatable runner and extending along the volute passageway of the concentric runner, means for simultaneously rotating both of said runners, and means 55 whereby the volute vane of the floating runner will continuously change position in relation to the walls of the volute passageway along which it extends to progressively force volumes of a fluid there- 60 along to be emitted from the inner end of the passageway.

18. A fluid compressor, comprising a stationary casing having an induction port through the wall thereof, a concentrically 65 rotating runner within the casing having a

plurality of disks supporting a volute vane, a volute floating vane intersticed with the first named vane, a cylindrical wall inclosing both of said vanes and formed integral with the terminating end of the floating 70 vane, means for driving said vanes in synchronism, and means for maintaining the floating vane in eccentric relation to the concentric vane.

19. A fluid compressor, comprising a stationary casing having an induction port through the wall thereof, a concentrically rotating runner within the casing having a plurality of disks supporting a volute vane, a volute floating vane intersticed with 75 the first named vane, a cylindrical wall inclosing both of said vanes and formed integral with the terminating end of the floating vane, flanges about the periphery of said wall, connecting means between said 80 flanges and disks whereby radial movement of said floating member in relation to said concentric member is permitted, means for rotating said members in synchronism, and means for maintaining said floating member 85 eccentrically of the concentric member.

20. A fluid compressor, comprising a stationary casing having an induction port through the wall thereof, a concentrically rotating runner within the casing having 90 a plurality of disks supporting a volute vane, a volute floating vane intersticed with the first named vane, a cylindrical wall inclosing both of said vanes and formed integral with the terminating end of the floating vane, flanges about the periphery of said wall, connecting means between said 95 flanges and disks whereby radial movement of said floating member in relation to said concentric member is permitted, 100 gear teeth about the peripheries of said disks and flanges, driving gears mounted on the inner wall of said stationary casing and adapted to mesh with said gear teeth, and means for limiting the radial movement of said floating member within a vertical plane.

21. A fluid compressor, comprising a stationary casing having an induction port through the wall thereof, a concentrically 115 rotating runner within the casing having a plurality of disks supporting a volute vane, a volute floating vane intersticed with the first named vane, a cylindrical wall inclosing both of said vanes and formed 120 integral with the terminating end of the floating vane, flanges about the periphery of said wall, connecting means between said flanges and disks whereby radial movement of said floating member in relation to said 125 concentric member is permitted, gear teeth about the peripheries of said disks and flanges, driving gears mounted on the inner wall of said stationary casing and adapted to mesh with said gear teeth, and 130

idler gears mounted similar to the driving gears and disposed diametrically thereof whereby the eccentric relation of said floating member with relation to the concentric member is maintained within a vertical plane.

In testimony whereof I have hereunto

set my hand in the presence of two subscribing witnesses.

RETLOW ROLKERR.
